UNITED STATES PATENT OFFICE

BULB LOADING APPARATUS

Donald L. Kingston, Marblehead, and Burleigh Leach, Hamilton, Mass., assignors to Sylvania Electric Products Inc., Salem, Mass., a corporation of Massachusetts

Application May 24, 1952, Serial No. 289,928

3 Claims.

1

This invention relates to the manufacture of electric lamps and similar devices employing a bulbous envelope and more particularly to apparatus for feeding bulbs to a sealing machine.

In the manufacture of electric lamps and other electrical devices in which a bulbous envelope is one of the components thereof, bulbs and mounts are fed to heads on a sealing machine. The heads are advanced to a plurality of work stations where sealing of the mount to the bulb is effected. In some cases the bulbs are fed to the sealing machine heads manually and in other cases the bulbs are fed automatically. Automatic feeding of bulbs is usually accomplished by means of a transfer mechanism which carries each bulb to a position above and in register with the bulb holder of a sealing machine head and then drops it into the bulb holder. In most cases this type of mechanism has performed the operation satisfactorily. However, some bulbs, due to their configuration, present more problems than others in effecting this transfer. One type of bulb in this category is known in the art as an S6-G4 bulb. The diameter of the cullet of S6-G4 bulbs is greater than the major diameter of the bulb itself. Feeding of this type of bulb by the conventional transfer mechanism just described is therefore not possible since the cullet is too large to pass between the fingers of the bulb holder.

Therefore, an object of this invention is to transfer bulbs automatically.

Another object is to automatically transfer bulbs, the cullets of which are of greater diameter than the major diameter of the bulb itself.

A further object is to automatically feed bulbs, the cullets of which are of greater diameter than the major diameter of the bulb itself, to the heads of a sealing machine.

A further object is to accomplish the above-mentioned objects at a minimum expense and with a minimum alteration of presently-employed apparatus.

These and other objects are attained in accordance with the principles of our invention as illustrated and described in the accompanying specific embodiment thereof by mounting a stationary cam adjacent to the path normally traveled by a bulb as it is fed to a sealing machine head and by pivotally mounting the bulb transfer head and providing it with a cam roller. The contour of the channel cut in the stationary cam is such that, as the cam roller moves there-through, the bulb carried by the bulb transfer head will be deflected sufficiently from the vertical to cause the cullet thereof to pass outside

of the fingers of the sealing machine bulb holder.

Another object is to provide a means for

automatically advancing the bulb to the sealing machine bulb holder.

Another object is to provide a means for

automatically advancing the bulb to the sealing machine bulb holder.

Another object is to provide a means for

automatically advancing the bulb to the sealing machine bulb holder.

Another object is to provide a means for

automatically advancing the bulb to the sealing machine bulb holder.

Another object is to provide a means for

automatically advancing the bulb to the sealing machine bulb holder.

Another object is to provide a means for

automatically advancing the bulb to the sealing machine bulb holder.

Another object is to provide a means for

automatically advancing the bulb to the sealing machine bulb holder.

Another object is to provide a means for

automatically advancing the bulb to the sealing machine bulb holder.

Another object is to provide a means for

automatically advancing the bulb to the sealing machine bulb holder.

Another object is to provide a means for

automatically advancing the bulb to the sealing machine bulb holder.

Another object is to provide a means for

automatically advancing the bulb to the sealing machine bulb holder.

Another object is to provide a means for

automatically advancing the bulb to the sealing machine bulb holder.

Another object is to provide a means for

automatically advancing the bulb to the sealing machine bulb holder.

Another object is to provide a means for

ports a rod 44 extending therethrough at the other end thereof. The shaft 42 is supported by arms 46.

Referring now to Figure 2, the shaft 42 has a block 48 mounted on the lower end thereof. The block 48 has a pin 50 projecting therefrom which rides in elongated slot 52 in lever 54. The lever 54 which is pivotally mounted on standard 56 at 5 58, is provided with a counter-weight 60. Cam roller 62 mounted on lever 54 rides on barrel cam 64. The rod 44, which is mounted on the free end of bulb transfer arm 40, has a block 66 mounted thereon, to which a vacuum line 68 is connected. The lower end of rod 44 is provided with a block 70 mounted thereon. Block 72, 15 which is fixedly mounted on block 70, supports bulb transfer suction head 74 which is pivotally mounted thereon by means of the spring-loaded pin 76. The bulb transfer suction head 74 is provided with a cam roller 78 mounted on a screw 79.

Referring now to Figure 3, the block 72 is fixedly attached to block 70 by screws 80. The block 72 has a pair of stop pins 82 projecting from a face thereof on opposite sides of the bulb transfer head 74 to define the limits of the oscillation of the bulb transfer head 74 about its pivot 76. Stationary cam 38 is adjustably mounted on bracket 34 by means of screws 84 which extend through elongated slots 86 in bracket 34. Cam 38 has a channel 88 cut therein, through which cam follower 78 rides as the bulb transfer head 74 carries bulb 90 downwardly to a position on the bulb holder 18 of head 14 above and in register with a mount 92 seated on the top of spindle 16.

Referring now to Figure 6, the block 72 is provided with a spring loaded ball bearing 94 which normally seats in a recess 96 in the adjacent face of bulb transfer head 74. The block 72 is provided with a boss 98 which serves as a seat for one end of spring 100 which loads pin 76 on which the bulb transfer head 74 is pivotally mounted. The bottom of the bulb transfer suction head 74 is provided with an opening 102 therein in which a gasket 104 is seated. The opening 102 is in register with a chamber 106 in the head 74. The chamber 106 is in communication with vacuum line 68 (Fig. 2), through a series of chambers 108 in head 74, 110 in block 72, 112 in block 70 and 114 in rod 44 (Fig. 6), and 116 in block 66 (Fig. 2).

The operation of the apparatus will now be described. Referring first to Figures 1 and 2, bulbs 90 are transferred from the bulb holding heads 23 on the bulb feeding turret 22 to the bulb holders 18 of the heads 14 on the lamp exhaust machine 10 by the bulb transfer head 74. Bulbs 90 are fed to the heads 23 on the turret 22 in any suitable manner. Crosshead 26 is reciprocated on bars 28 to move a head 23 on the bulb feeding turret 22 into and out of a bulb transfer position wherein a bulb 90, seated in a head 23, is in register with the bulb transfer head 74 and a head 14 of the lamp exhaust machine 10 and is disposed therebetween as is shown in Figure 2. Reciprocation of the crosshead to move the turret 22 from the position shown in phantom to the position shown in solid in Figure 1 may be effected by some suitable mechanism, such as by reciprocation of the rod 29 (Fig. 1) for example.

Referring now to Figure 2, the bulb transfer suction head 74 is moved downwardly into contact with the top of the bulb 90 and then moved upwardly with the bulb 90 held therein. This reciprocation of the bulb transfer suction head

74 is effected by the barrel cam 64 through cam roller 62, lever 54, shaft 42, transfer arm 40 and rod 44. Immediately after the suction head 74 has lifted the bulb 90 from the head 23 of turret 22, the turret 22 is retracted to the position shown in phantom in Figure 1 and at the same time indexed (by means not shown) one station to move a bulb-carrying head 23 into position for the next delivery stroke of the turret 22. The shaft 42 then moves downwardly to effect delivery of the bulb 90 by the suction head 74 to the bulb holder 18.

Referring now to Figure 4, as the suction head 74 moves downwardly with the bulb 90, the cam follower 78 moves through the irregular channel 88 cut in stationary cam 38. Since the suction head 74 which carries the bulb 90 is pivotally mounted at 76, the head 74 is deflected to the right (Fig. 4) and the cullet 91 of bulb 90 is displaced sufficiently to move it out of register with the bulb holding fingers 28 of bulb holder 18. The bulb 90 moves downwardly in this canted position until after the cullet 91 thereof has passed the bulb holding fingers 28 of the bulb holder 18. The contour of the channel 88 is such that at this point the suction head 74 is returned to the vertical position and the remainder of the delivery stroke thereof is completed and the bulb 90 is seated on the fingers 28. The vacuum line 68 (Fig. 1) is then interrupted momentarily to effect release of the bulb 90 from the suction head 74. The suction head 74 then returns to its normal starting position. When cam follower 78 moves out of channel 88 in cam 38 the suction head 74 is substantially vertical. It is maintained in this position and prevented from freely oscillating about its pivot 76 by the ball bearing 94 (Fig. 6) which seats in recess 96.

What we claim is:

1. Apparatus for feeding a bulb to a bulb holder comprising: a pivotally mounted bulb transfer head disposed above and in register with the bulb holder; a cam follower mounted on said head; means for reciprocating said bulb transfer head toward and from the bulb holder to effect delivery of a bulb carried by said bulb transfer head to the bulb holder; and a stationary cam disposed adjacent to the path traversed by said bulb transfer head, said cam having an irregular path formed therein through which the cam follower travels during the reciprocation of said bulb transfer head whereby the bulb transfer head is rotated about its pivot and the bulb carried by said head is displaced from a substantially vertical posture for an interval during the transfer operation and then returned to the vertical.

2. Apparatus for feeding a bulb to a bulb holder comprising: a transfer arm; a bulb transfer head pivotally mounted on said arm and disposed above and in register with the bulb holder; a cam follower mounted on said head; means for reciprocating said transfer arm to effect movement of the bulb transfer head pivotally mounted thereon toward and from the bulb holder to effect delivery of a bulb carried by said bulb transfer head to the bulb holder; and a stationary cam disposed adjacent to the path traversed by said bulb transfer head, said cam having an irregular path formed therein through which the cam follower travels during the reciprocation of said bulb transfer head whereby the bulb transfer head is rotated about its pivot and the bulb carried by said head is displaced from a substantially verti-

cal posture for an interval during the transfer operation and then returned to the vertical.

3. Apparatus for feeding a bulb to a bulb holder having a plurality of bulb-supporting fingers defining a seat for the bulb, said apparatus comprising: a transfer arm; a bulb transfer head pivotally mounted on said arm and disposed above and in register with the bulb holder; a cam follower mounted on said head; means for reciprocating said bulb transfer head toward and from the bulb holder to effect delivery of a bulb carried by said bulb transfer head to the seat defined by the bulb-supporting fingers of the bulb holder; and a stationary cam disposed adjacent to the path traversed by said bulb transfer head, said 15

cam having an irregular path formed therein through which the cam follower travels during the reciprocation of said bulb transfer head whereby the bulb transfer head is rotated about its pivot and the cullet of the bulb carried by said head passes outside the seat defined by the bulb supporting fingers as the bulb approaches its seat on the holder.
